UNITED STATES PATENT OFFICE.

HERBERT L. FISH, OF SPRINGFIELD, OHIO, ASSIGNOR TO HARRY C. DOWNEY, OF SPRINGFIELD, OHIO.

BLOWTORCH.

Application filed December 26, 1924. Serial No. 758,059.

This invention relates to improvements in blow torches and it particularly relates to a torch which has a fuel tank in which the fuel is maintained under pressure to feed 5 the same to the generator and burner.

An object of my invention is to provide an arrangement by which initial air pressure may be applied to the fuel in the tank and thereafter the pressure automatically 10 maintained by vaporization of the fuel in the tank due to the heat of the burner.

A further object of the invention is to provide a torch which is simple and economical in construction and efficient in operation.

In the accompanying drawings:

Fig. 1 is a top plan view of a torch embodying the improvements.

Fig. 2 is a side elevation of the same.

Fig. 3 is a view partly in side elevation and partly in vertical section on line 3—3 of Fig. 1.

Referring to the drawings, 1 represents the fuel tank which in the present case is provided with an outwardly flared base 2 to form a support. The tank is provided with an air pump 3 of any usual and suitable form whereby air may be forced into the tank to provide an initial pressure upon the fuel in a manner common in torches of this character. Securely fastened to the upper portion of the tank with an air tight joint is a socket member 4 to receive the reduced lower end of a stem 5. The upper end of the stem is reduced and threaded to receive the threaded bore of a boss 6 of a casting 7. This casting 7 is provided with an integrally formed generating chamber 8 to one end of which is connected one end of a tube 9, the other end of the tube being connected with the threaded nipple 10, projecting from the tank, by the packing nut 11. A second tube 12, connected with the nipple in any suitable manner so as to communicate 45 with the tube 9, extends to the extreme bottom of the tank as shown in dotted lines in Fig. 2.

The other end of the generating chamber 8 communicates through a reduced orifice 13 with the vertical portion 14 of a L-shaped passageway the horizontal portion 15 of which has its outer end closed by a cap 16 and its inner end communicating through a reduced orifice 17 with a burner tube 18. A needle valve 19 serves to control

the orifice 13, and the cap 16 allows access to the orifice 17 for cleaning purposes.

The rear portion of the burner tube 18 is exteriorly threaded and screwed in an integral extension 20 of the casting 7 and is fitted closely against the forward wall of the passageway 14 in communication with the orifice 17. The rear end of the burner tube adjacent the orifice 17 forms a mixing chamber and is provided with a series of four openings 21 to admit air, and the central portion of the tube is also provided with a series of air openings 22, six in number in the present case. The rear end of the enlarged forward portion 18' is provided with 65 flame jet openings 23, four in number in the present case. The tube 9 is coiled about the enlarged portion 18' as indicated at 9' with the rear coil in immediate proximity to the openings 23 so as to receive the direct 70 heat of the flames emitted therethrough.

Inserted upon the stem 5 is a cup member 24 which rests upon a collar 25 placed about the socket member 4; the collar 25, the socket 4 and reduced portion of the stem 5 80 being secured together by the pin 26.

In operation, the pump 3 is operated to place an initial pressure of air upon the fuel in the tank 1, and gasoline or other fuel is placed in the cup member 24 and ignited so as to initially heat the generating chamber 8. The valve 19 is then adjusted to admit the proper amount of fuel to the burner tube. The flames emitted from the flame jet openings 23 heat the coils 9' of 85 the fuel tube 9, the heat being carried by conductivity to the tube 12 in the tank 1 which heats the fuel in the tank and vaporizes the same to an extent to place the necessary pressure upon the fuel to force it through the 90 tube 9, generating chamber 8 and passage 14 to the burner tube. This latter result is accomplished by reason of the fact that the coils 9' of the tube are located in comparatively close proximity to the pipe 12 so 95 that the pipe 12 is kept in a sufficiently hot condition to generate vapor in the tank, and it has been found in practice that this arrangement furnishes the required pressure in the fuel tank to uniformly supply fuel 100 to the burner without the necessity of pumping any additional air into the tank so long as the torch is kept in continuous operation. While the tubes 9 and 12 in the present case are shown as separate tubes closed aligned 110

2
together, yet if desired, these tubes may be made in one piece. In the present case the tube 12 forms in effect an extension of the tube 9 and receives the heat conducted by 5 the same.

Having thus described my invention, I claim:

In a blow torch, a tank, a generator and a burner tube, means for supporting same by 10 and immediately above the tank and in close proximity thereto, a fuel tube independent of said supporting means coiled about said burner tube immediately above said tank,

one end of said fuel tube being connected with said generator and the other end of 15 said fuel tube extended immediately downward from said coil and projecting into said tank in proximity to the lower portion of the interior thereof, said burner tube being provided with flame jet openings in proximity to said coil to heat said coil and cause the heat to be conducted by said tube to the fuel in said tank, said fuel tube forming the sole means of conducting heat to said fuel. 20
